INVENTOR

2 Salvadore Bertocchi
BY J. H. Walker

ATTORNEY

UNITED STATES PATENT OFFICE.

SALVATOR BERTOCCHI, OF NEWARK, NEW JERSEY.

WIND MUSICAL INSTRUMENT.

1,252,653

Specification of Letters Patent. Patented Jan. 8, 1918.

Application filed July 11, 1917. Serial No. 179,993.

To all whom it may concern:

Be it known that I, SALVATOR BERTOCCHI, a citizen of Italy, and resident of Newark, in the county of Essex and State of New Jersey, have invented certain new and useful Improvements in Wind Musical Instruments, of which the following is a specification:

This invention relates to wind instruments, and my improvement is directed to a bellows operated reed, such as may be contained within a doll or other toy, for the production of musical notes upon the application of pressure.

The main object of my invention is to provide for automatic variation of the musical sound produced by a bellows actuated reed, functioning automatically, to impart variable movement to said valve in each air expelling stroke of the bellows.

Other features and advantages of my said invention will hereinafter appear.

Figure 1 is a plan view of my improved apparatus.

Fig. 2 is a section on the line 2—2 of Fig. 1, and

Fig. 3 is a partial sectional view showing the sound box and reed.

In the example of my invention illustrated herewith, let 1 indicate the base, and 2 the upper member of a bellows, normally spread apart by a spring 3, and whose inclosure and hinge may be composed of paper or other flexible covering 4.

The top 2 has an orifice 5 therethrough, and contiguous to said orifice is the vibratory end of a reed 6, which may lie upon the top 2, and communicate, at its free end, with a sound box 7, the latter also being mounted upon the top 2, near the forward end thereof. A sheath 8, which may be of metal, extends over the vibratory end of the reed, to inclose the latter; and said sheath, reed and sound box may all be firmly secured upon the top 2, in air tight connection therewith, as by the embedding application of glue or other adhesive material.

The sound box 7 has an air exit orifice 9, controlled by a valve 10; and also an intake orifice 11.

It is through the variable operation of the valve 10, in the course of a single air expelling stroke of the bellows, that I am able to effect the production of different musical

sounds from a single reed. The mechanism employed by me in accomplishing this purpose is as follows:

Secured to the base 1, at its free end, is a post 12, which extends upwardly, through a portion of the height of the bellows, as expanded, said post having a curved terminal face 13, for a purpose to be described hereinafter.

The valve 10 is secured upon the sound box 7, at the rear of the orifice 9, and is of spring-like material, having a pad-like covering 14 to contact with the box surface about orifice 9. An upwardly extending fold in the material of valve 10, between its point of connection with the sound box and orifice 9, is provided to position the fulcrum of said valve near to orifice 9, which permits the soldering of the valve to the sound box to be performed at a more distant point, this arrangement also permitting the valve operation, in opening and closing, to be performed at a more acute angle, and therefore more quickly responsive.

The valve 10 extends over the forward edge of top 2, and is bent downwardly in the form of a tongue 15, with a curved terminal surface 16, which normally lies in opposed relation to the face 13 of post 12, said faces 16 and 13 being, in normal position of the device, separated by an intervening space.

With the application of pressure upon the bellows to close together its top and base members, the rush of air outwardly through the reed and sound box will produce musical sounds, which by means of the mechanical valve control described, will produce successive notes of different pitch, the return or expanding stroke of the bellows being effected by the action of the spring 3.

This stated result is achieved by the tongue surface 16 meeting the face 13 of post 12; when the members 1 and 2 are pressed together, the pressure thus applied to valve 10, causing it to yield at its fulcrum, and thus to open orifice 9, emitting a note; continued closing movement of the bellows then causing the tongue face outside the same to slip off the post face, so that the tension of the valve relaxes and the valve becomes seated again to close orifice 9. Still however continuing the closing of the bellows, the tongue 15 will travel freely

until its upper portion 17 meets the post face 18, and then further inward movement of the bellows causes the post to again lift the valve for the emission of another note.

Thus, in a complete inward stroke of the bellows, the valve is twice actuated by the post 12.

I claim:

1. In a wind musical instrument comprising a bellows having base and top portions, the combination, with a sound box upon said top portion, and a reed therefor, said sound box having an exit orifice, of a forwardly opening spring valve for said orifice, a tongue extended downwardly from said valve, said tongue having a curved terminal portion and an upper engaging portion; together with a post extended upwardly from said base portion, in the path of movement of said tongue, whereby said tongue terminal and upper portions successively engage said post to open said valve, continued closing movement of said bellows causing said terminal portion, after operatively engaging said post, to slip therefrom and thus release the valve prior to engagement of the post by the rearward portion of said tongue.
2. In a wind musical instrument comprising a bellows having base and top portions, the combination, with a sound box upon said top portion, and a reed therefor, said sound box having an exit orifice, of a forwardly opening spring valve for said orifice, a tongue extended downwardly from said valve, and a post extending upwardly from said base portion, the end of said post being in opposed, spaced relation to said tongue, and said tongue having forward and rearward engaging portions, whereby in closing said bellows the tongue forward portion meets the post, causing the valve to open, said forward portion then slipping off the post, causing the valve to close, and finally, the rearward portion of the tongue meets the post and thus again lifts the valve.

2. In a wind musical instrument comprising a bellows having base and top portions, the combination, with a sound box upon said top portion, and a reed therefor, said sound box having an exit orifice, of a forwardly opening spring valve for said orifice, a tongue extended downwardly from said valve, said tongue having a curved terminal portion and an upper engaging portion; together with a post extended upwardly from said base portion, in the path of movement of said tongue, whereby said tongue terminal and upper portions successively engage said post to open said valve, continued closing movement of said bellows causing said terminal portion, after operatively engaging said post, to slip therefrom and thus release the valve prior to engagement of the post by the rearward portion of said tongue.

Signed at city of Newark in the county of Essex and State of New Jersey this second day of July A. D. 1917.

SALVATOR BERTOCCHI.
